UNITED STATES PATENT OFFICE

147,113

DESIGN FOR A COCKTAIL SHAKER

Andrew Cravaritis, Roslyn, N. Y.

Application May 8, 1946, Serial No. 129,444

Term of patent 14 years

(Cl. D2—3)

To all whom it may concern:

Be it known that I, Andrew Cravaritis, a citizen of the United States, residing at Roslyn, in the county of Nassau and State of New York, have invented a new, original and ornamental Design for a Cocktail Shaker, of which the following is a specification; reference being had to the accompanying drawing, forming part thereof.

Fig. 1 is a perspective view of a cocktail shaker showing my new design;

Fig. 2 is a top plan view thereof; and

Fig. 3 is a vertical sectional view taken on the line 3—3 in Fig. 2.

I claim:

The ornamental design for a cocktail shaker, substantially as shown.

ANDREW CRAVARITIS.
